(57) **CLAIM**

The ornamental design for a handle, as shown and described.

DESCRIPTION

In a preferred embodiment, the nature of this product is as a plumbing handle and escutcheon which is primarily useful for controlling a rotatable valve stem.

FIG. 1 is a left, top, front perspective view of a handle embodying my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a top plan view of a second embodiment, the front elevational view being a mirror image of that shown in FIG. 2, the right side elevational view being a mirror image of that shown in FIG. 4, the left side elevational view being a mirror image of that shown in FIG. 5, the rear elevational view being a mirror image of that shown in FIG. 6, and the bottom plan view being a mirror image of that shown in FIG. 7.

The broken line representation of mounting structure in FIG. 7 is for the purpose of illustration only, and forms no part of the claimed design.
